UNITED STATES PATENT OFFICE.

GEORG OBAD, OF BELLEVILLE, ILLINOIS.

POLISH-RECEPTACLE.

1,115,095.

Specification of Letters Patent. Patented Oct. 27, 1914.

Application filed July 27, 1914. Serial No. 853,455.

To all whom it may concern:

Be it known that I, GEORG OBAD, a subject of the King of Hungary, residing at Belleville, in the county of St. Clair and State of Illinois, have invented certain new and useful Improvements in Polish-Receptacles, of which the following is a specification, reference being had therein to the accompanying drawing.

10 This invention relates to polish receptacle, especially designed to contain emery, and has for its object to provide a receptacle of such class, in a manner as herein-after set forth, with means to constitute 15 a polish reservoir surrounded by a collecting trough for the purpose of collecting polish which is thrown out of the reservoir when the polish is applied to an article.

Further objects are to provide a polish 20 receptacle for the purpose set forth which is simple in its construction and arrangement, strong, durable, efficient and convenient in its use, readily set up and comparatively inexpensive to manufacture.

25 With the foregoing and other objects in view the invention consists of the novel construction, combination and arrangement of parts hereinafter more specifically described and illustrated in the accompanying 30 drawings, wherein is shown an embodiment of the invention, but it is to be understood that changes, variations, and modifications can be resorted to which come within the scope of the claim hereunto appended.

35 In the drawings wherein like reference characters denote corresponding parts throughout the several views: Figure 1 is a perspective view of a polish receptacle in accordance with this invention, and Fig. 2 40 is a cross sectional view thereof.

The polish receptacle is designed primarily for use in application of emery to an article for polishing it, the article being revolved in a reservoir to be presently referred to and during the revolution of the article certain of the emery will remove from the reservoir and in most instances be lost and associating with the reservoir is a

collecting trough to gather the emery which otherwise would be wasted.

50 Referring to the drawings in detail, 1 denotes a rectangular frame which constitutes a supporting base and mounted upon said base is a collecting trough comprising a rectangular bottom 2 of greater width than the width of the side bar of the frame 1. Projecting from the bottom 2 are outer side walls 3, 4 and outer end walls 6, 7. The trough further includes inner side and end walls 8 which oppose the outer side and end 60 walls and form a collecting chamber 9. The inner, side and end walls are of a materially greater height than the outer side and end walls and constitute supports, and said inner side and end walls are flush with the 65 inner faces of the bars of the frame 1. Suspended within the frame 1 is a tank 10, which constitutes a reservoir 11, the side and end walls of the tank 10, are formed with outwardly projecting lateral flanges 12, 70 which are mounted upon the top edges of the inner side and end walls of the collecting trough whereby said tank 10 is suspended within the frame 1. Any emery discharged from the reservoir 11, during the polishing 75 operation, will be collected in the chamber 9.

What I claim is:—

A polish receptacle comprising a rectangular frame constituting a base, a collecting trough mounted thereon and including outer 80 side and end walls and inner side and end walls and a bottom forming thereby a collecting chamber, a tank extending in said frame and provided with lateral flanges mounted upon the top edges of said inner 85 side and end walls of said collecting trough thereby suspending the said tank, said inner side and end walls of said collecting trough being of greater height than the outer side and end walls of said collecting trough. 90

In testimony whereof I affix my signature in the presence of two witnesses.

GEORG OBAD.
